UNITED STATES PATENT OFFICE.

HENRY F. SCHMIDT, OF LANSDOWNE, PENNSYLVANIA, ASSIGNOR TO WESTINGHOUSE ELECTRIC & MANUFACTURING COMPANY, A CORPORATION OF PENNSYLVANIA.

TURBINE-BLADE SHROUDING.

Application filed September 12, 1925. Serial No. 56,016.

My invention relates to elastic fluid turbines, more particularly to the blading or buckets thereof, and has for its object the provision of apparatus of the character designated which shall be sturdy of construction, simple and easy of manufacture and which shall render the turbine highly efficient.

Apparatus embodying features of my invention is illustrated in the accompanying drawings forming a part of this specification wherein Fig. 1 is a fragmentary longitudinal sectional view of a turbine having my invention applied thereto; Fig. 2 is a partial sectional view of the turbine rotor taken along the plane II-II of Fig. 1; Fig. 3 is a developed plan view of a partial row of buckets with the shrouding removed; and Fig. 4 is a perspective view of my improved shrouding.

As is well known in the art to which my invention relates, a popular design of a relatively small type of elastic fluid turbine embodies a rotor having open U-shaped buckets milled or otherwise provided in the surface thereof. In operation, motive fluid is expanded through a suitable nozzle and is directed into the buckets for driving the rotor. While the construction described provides a very sturdy structure which is remarkably free from difficulties in operation, steam or other motive fluid in its passage in and out of the open buckets produces eddies in the flow that, to a certain extent, minimize the efficiency of the turbine. It is also well-known in the art that if a turbine blade or bucket can be so formed as to offer a tubular path for the motive fluid flow, eddies are avoided and the efficiency of the turbine is increased. It is accordingly the particular object of my invention to provide a bucket construction of the general character described wherein the motive fluid path therethrough is closed on its sides so as to be tubular in cross section and eddies are avoided.

In accordance with my invention I provide a shrouding, or cover, for open U-shaped turbine buckets in the form of a strip of metal having a series of inclined U-shaped projections or lugs thereon which enter into the buckets the distances necessary to provide tubular passages through the buckets of the desired proportions for the motive fluid. Preferably the shrouding is applied to buck-

ets formed in the inner periphery of an overhanging flange of the rotor on account of ease of application and retention in place, though it will be apparent that it may be applied to open buckets formed in various ways in a rotor and also materially add to the efficiency of the machine.

Referring now to the drawing for a better understanding of my invention, I show a turbine having a casing 10 and a rotor 11, mounted on a shaft 12. The rotor 11 is provided with an overhanging flange 13 in which is formed a series of buckets 14-14. The buckets 14-14 may readily be formed by milling into the material of the overhanging flange. Steam or other motive fluid is expanded through a suitable nozzle 16, directed into the buckets 14-14 and after performing useful work therein passes outwardly of the turbine casing through an exhaust opening 17.

Referring to Figs. 2 and 3 it may be seen that, without some means for guiding the motive fluid in the buckets, eddies of flow are free to be set up therein. I accordingly provide a shrouding or cover 18 for the buckets which is so shaped as to form, with the buckets, a continuous tubular passage for the motive fluid passing therethrough which prevents the formation of eddies and permits the maximum amount of energy to be abstracted from the motive fluid. Referring to Fig. 4 it may be seen that the shrouding or cover 18 is comprised of a series of slanting U-shaped projections 19-19 overlapping each other so as to form a continuous strip. In practice I form this strip by drop forging the metal in a suitable die and bend it around in the form of a ring for covering the buckets milled into the inner periphery of the flange 13. Upon insertion, the projections 19-19 lie within the open ends of the buckets and the outer surfaces of the projections, shown at 21-21 in Fig. 4, lie flat against the flat surfaces of the buckets as may be seen in Fig. 2. Where the buckets are milled on the inner surface of an overhanging flange of the rotor, centrifugal force in operation acts to hold the shrouding in close contact with the buckets. In such cases it is only necessary to secure the shrouding or cover 18 to a few points around the rotor as at 22-22 in Fig. 2.

In order that the motive fluid path through the buckets formed by the projec-

tions 19—19 with the buckets may be of the proper proportions, it may be necessary to cut away notches in the entrance edges of the blades as shown at 23—23 in Fig. 3. The 5 rounded ends of the projections 19—19 enter into the notches 23—23 in such a way that, if desired, the motive fluid passage through the bucket may be uniform throughout. The 10 size or proportions of the motive fluid passage may otherwise be modified by varying the width of the strip 18 in relation to the width of the buckets. It will be apparent therefore that by modifying the notches 23—23 and varying the width of the strip 18 15 and contour of the projections 19—19, a tubular motive fluid path designed to meet all practical conditions of motive fluid flow may be designed.

From the foregoing it will be apparent 20 that I have devised a shrouding for turbine buckets adapted to provide a motive fluid path therethrough of the highest efficiency, which is simple of manufacture, sturdy of construction and easy of application.

25 While I have shown my invention in but one form, it will be obvious to those skilled in the art that it is not so limited, but is susceptible of various changes and modifications, without departing from the spirit 30 thereof, and I desire, therefore, that only such limitations shall be placed thereupon as are imposed by the prior art or as are specifically set forth in the appended claims.

What I claim is:

35 1. In a turbine, the combination of a rotor having a series of U-shaped buckets formed therein and opening radially inwardly, and a shrouding for said buckets comprising a strip of material with a series of projections thereon fitting into the buckets and forming therewith a tubular U-shaped passage for the motive fluid.

40 2. In a turbine, the combination of a rotor having a series of buckets formed around 45 the periphery thereof and opening radially inwardly, and a shroud for said buckets comprising a strip of metal narrower than the buckets and having a series of U-shaped 50 projections thereon fitting into the open ends of the buckets forming therewith a tubular passage for the motive fluid.

55 3. In a turbine, the combination of a rotor having an overhanging flange with a series of buckets formed in the inner periphery thereof, and a shroud for said buckets comprising a strip of metal having a series of U-shaped 60 projections thereon fitting into the open ends of the buckets and forming therewith a tubular passage for the motive fluid.

65 4. In a turbine, the combination of a rotor having an overhanging flange with a series of buckets formed in the inner periphery thereof, and a shroud for said buckets com-

prising a strip of metal having a series of slanting U-shaped projections thereon fitting into the open ends of the buckets and extending inwardly thereof forming a closed U-shaped passage for the motive fluid.

65 5. In a turbine, the combination of a rotor having an overhanging flange with a series 70 of buckets formed in the inner periphery thereof, and a shroud for said buckets comprising a strip of metal having a series of slanting U-shaped projections thereon fitting into the open ends of the buckets 75 and extending inwardly thereof forming a closed U-shaped passage for the motive fluid and secured to the buckets in one or more places around the periphery of the rotor.

80 6. In a turbine, the combination of a rotor having an overhanging flange with a series 85 of buckets formed in the inner periphery thereof, and a shroud for said buckets comprising a circular strip of metal having a series of U-shaped projections thereon adapted to extend into the open ends of the buckets forming therewith a U-shaped passage for the motive fluid and held in place mainly by centrifugal force.

90 7. In a turbine, the combination of a rotor having an overhanging flange with a series 95 of buckets formed in the inner periphery thereof, and a shroud for said buckets comprising a circular strip of metal narrower than the buckets and having a series of U-shaped 100 projections thereon adapted to extend into the open ends of the buckets; curved slots formed in the inlet edges of the buckets for the reception of the U-shaped projections, and means joining the circular strip to one or more buckets around the periphery of the rotor.

105 8. In a turbine, the combination of a rotor having an overhanging flange with a series 110 of buckets formed in the inner periphery thereof, a series of curved slots formed in the entrance edges of the buckets, and a shrouding for the buckets comprising a strip of metal having a series of curved 115 projections thereon fitting into the slots and extending inwardly of the buckets forming a tubular curved passage for the motive fluid.

120 9. A shroud for turbine buckets formed in the inner periphery of an overhanging flange of the turbine rotor comprising a strip of metal formed with a series of inclined U-shaped projections on one side thereof and adapted to lie in the open ends of the buckets to form a tubular curved passage for the motive fluid.

In testimony whereof, I have hereunto subscribed my name this third day of September 1925.

HENRY F. SCHMIDT.
